(57) **CLAIM**

The ornamental design for a shopping cart as shown and described.

DESCRIPTION

This application is related to and incorporates by reference U.S. patent application Ser. No. 29/857,743 entitled "Shopping Cart" filed on an even date herewith. It is understood that any material in U.S. patent application Ser. No. 29/857,743 that is not present in this application forms no part of the claimed design.

FIG. 1 is a rear, perspective view of the shopping cart showing a first embodiment of our new design;

FIG. 2 is a front view thereof;

FIG. 3 is a rear view thereof;

FIG. 4 is a right side view thereof;

FIG. 5 is a top view thereof;

FIG. 6 is a bottom view thereof; and,

FIG. 7 is a left side view.

In the drawings, the broken lines depict unclaimed subject matter only and form no part of the claimed design. The features shown in bolded broken lines indicate the bounds of the claimed design and otherwise form no part of the claimed design.
